Jordan L. Mott
Letters Patent

8983 1/2 X

The schedule referred to in these Letters Patent and making part of the same containing a description in the words of the said Jordan L. Mott himself of his improvements in the Stove

To all whom it may concern

Be it known that I Jordan L. Mott of the City of New York in the state of New York have invented an improvement in the manner of constructing the stoves for which letters patent of the United States were granted to me on the thirtieth day of December 1833, and I do hereby declare that the following is a full and exact description of my said improvement. The combined ^{two} ~~one~~ and patented by me, as above was intended to unite the advantage of the close stove with that of an open fire place and I have heretofore been in the practice of casting the front part thereof in four separate pieces, namely, a front piece two jamb, and the inclined plane, a curved plate (described in my former specification) which conveys the fuel into the grate, but I have found this procedure to be productive of considerable inconvenience, inasmuch as the ordinary defects in casting frequently rendered it difficult to adapt these pieces properly to each other, and more especially from the burning out of the lower edge of the inclined or curved plate. To obviate the first of these difficulties, I now cast the entire front consisting of the inclined or curved plate, the horizontal plates above it forming the front of the close part of the stove, and the two jamb, form a single pattern in one piece with the exception of the lower and middle part of the inclined or curved plate, which in order to obviate the second difficulty above alluded to namely, the burning out of that part thereof which is in contact with the fire, usually cast in a separate piece. This separate piece I make of sufficient length and width to sustain the whole effect of the fire so far as the burning out of the curved or inclined plate is concerned, the separate piece to cast is received in a recess corresponding therewith in

the inclined or curved plate and is retained in its place by suitable ledges and a screw or pin attaching the two parts to each other. To give strength and durability to this separate piece I form a ridge or ridge along or across the outside thereof, leaving the inside smooth for the ready descent of the fuel. Although I prefer to make a separate plate in the way described, as in case of its burning out, it is then readily removed without disturbing any other part. I sometimes merely form ridges or rills upon the outside of the inclined or curved plate, cast in one continuous piece with the parts before named, such ridges or rills occupying the parts liable to be burnt out, and considerably increasing its durability.

What I claim as my improvement upon the combined stove as patented by me at the date mentioned above is the casting the entire front thereof in one piece in the manner set forth, with the addition of the ridge or rills upon that part of the inclined or curved plate which is directly exposed to the action of the fire. I also claim the making or casting of that portion of the inclined or curved plate which is exposed in a separate and distinct piece in the manner and for the purpose herein set forth.
